UNITED STATES PATENT OFFICE.

ERNEST JACQUES ROUX AND LOUIS URIEL FATIO, OF GENEVA, SWITZERLAND, ASSIGNEES TO VACHERON & CONSTANTIN, OF SAME PLACE.

WATCH-REGULATOR.

SPECIFICATION forming part of Letters Patent No. 291,760, dated January 8, 1884.

Application filed October 19, 1883. (No model.)

To all whom it may concern:

Be it known that we, ERNEST JACQUES ROUX and LOUIS URIEL FATIO, both of Geneva, Switzerland, have invented a new and 5 Improved Watch-Regulator, of which the following is a full, clear, and exact description.

The object of our invention is to provide a new and improved device for adjusting the hair-spring regulator of a watch very finely 10 and accurately.

The invention consists of the several combinations and arrangements of parts, substantially as hereinafter fully set forth and claimed.

Reference is to be had to the accompanying 15 drawings, forming part of this specification, in which similar letters of reference indicate corresponding parts in all the figures.

Figure 1 is a plan view of our improved watch-regulator. Fig. 2 is a longitudinal sectional elevation of the same on the line *x x*, Fig. 1. Fig. 3 is a side view of the plates for holding the adjusting-screw, showing the toothed wheel removed. Fig. 4 is a like view, showing the toothed wheel in place. Fig. 5 25 is a longitudinal sectional view, showing the manner in which the screw-spindle is held.

The arbor of the fly-wheel or balance-wheel A is held in the end of a bridge, B, fastened to the bed-plate of the works in the usual manner. The end of the spiral spring C, for operating the fly or balance wheel, is held between two prongs, D, projecting from one end of a pivoted index-lever, E, which is provided at the opposite end, on its bottom surface, with a 30 knife-edge, E', which rests in the thread of the screw-spindle R. The bridge B is provided with a scale, G, in the usual manner. The screw-spindle R is provided at one end with a small toothed head or wheel, H, and 35 the bridge is provided with a transverse groove, I, for receiving the spindle. A semicircular plate, J, is provided at the end with two prongs, J' and J'', of which the latter is provided with a recess, a, for receiving the toothed wheel H. 40 The letters "F" and "S," or their equivalents, are stamped or otherwise produced on the ends of the prong J' each side of the recess a. The plate J is provided with two pins, K, projecting from its under side. A like 45 semicircular plate, L, is provided at each end with a prong, forming a hook, M, adapted to

pass around the thinner ends of the screw-spindle R. The plate L is provided with apertures, through which the pins K can pass. The ends of the screw-spindle R are placed 55 in the hooks M, and the plate J is placed on the plate L, so that the screw-spindle will be held between the hooks M and the plate J, the toothed wheel or head H passing into the recess a, as stated. The plates J and L are 60 then placed on the rear end of the bridge, and are secured on the bridge by the pins K, passing into suitable apertures in the bridge, and by screws O, screwed through the plates J L and the rear end of the bridge. As the knife- 65 edge E' of the pointer or indicator E rests in the threads of the screw-spindle R, the end of the pointer can be moved laterally—that is, toward either side of the bridge—by turning the toothed wheel or head H in either one 70 direction or the other. The pointer or indicator will be moved a greater or less distance, according to the pitch of the screw.

By means of the above-described device the indicator or pointer can be adjusted very 75 finely and nicely, for by turning the head or wheel H the distance of one tooth the pointer will be moved a distance which is so minute that it could not be adjusted by hand, as in the usual regulators. 80

Having thus described our invention, what we claim as new, and desire to secure by Letters Patent, is—

1. In a watch-regulator, the combination, with a pointer-lever, of the screw-spindle, 85 with its ends held between the semicircular plates, said spindle having a toothed head or wheel arranged in a recess of one of said plates, substantially as and for the purpose set forth.

2. In a watch-regulator, the combination, 90 with a pointer-lever, of the plate J, the plate L, provided with hooks M M, and the screw-spindle R, having its ends held between the plate J and the hooks M, substantially as herein shown and described, and for the purpose 95 set forth.

3. In a watch-regulator, the combination, with the plate J, having two prongs, J' J'', of which the latter is provided with a recess, a, of the plate L, provided with the hooks M, the screw-spindle R, held between the plate J and the hooks M, and the toothed wheel or head 100

H, mounted on the end of the screw-spindle, and fitting in the recess *a* in the plate J, substantially as herein shown and described, and for the purpose set forth.

5 4. In a watch-regulator, the combination, with the pointer-lever E, of the plate J, provided with prongs J' J'', of which the latter has a recess, *a*, the pins K, projecting from the plate J, the plate L, provided with hooks to M, of the screw-spindle R, held between the

plate J and the hooks M, and of the toothed wheel or head H on the end of the spindle R, substantially as herein shown and described, and for the purpose set forth.

ERNEST JACQUES ROUX.
LOUIS URIEL FATIO.
